UNITED STATES PATENT OFFICE.

CHARLEY W. LYNCH, OF TRINITY, TEXAS.

TRACK-CLEANER.

1,148,392.

Specification of Letters Patent.

Patented July 27, 1915.

Application filed May 7, 1915. Serial No. 26,600.

To all whom it may concern:

Be it known that I, CHARLEY W. LYNCH, a citizen of the United States, residing at Trinity, in the county of Trinity and State 5 of Texas, have invented certain new and useful Improvements in Track-Cleaners; and I do hereby declare the following to be a full, clear, and exact description of the invention, such as will enable others skilled 10 in the art to which it appertains to make and use the same.

This invention relates to new and useful improvements in track cleaners and the principal object of the invention is to provide a track cleaner particularly adapted 15 for use in saw mills, planing mills and the like, where it is necessary to keep tracks clear of shavings, saw dust and the like.

Another object of the invention is to provide a track cleaner which has removable 20 and renewable plugs so that the wear on the plugs may be taken up to insure the proper position of the cleaner with relation to the wheels, of the car on which the device is used.

A further object of the invention is to provide a cleaner wherein plugs are provided which may be renewed and which may be formed of a suitable wear resisting material.

30 A still further object of this invention is to provide a body for the cleaner which is so arranged as to permit the plugs to be easily renewed.

With these and other objects in view, the 35 invention consists in the novel combination and arrangement of parts which will be fully set forth in the following specification and accompanying drawings, in which:—

40 Figure 1 is a side view in elevation of a track cleaner constructed in accordance with this invention showing the same applied to a wheel. Fig. 2 is a front view in elevation of the cleaner showing the same attached to a pair of wheels and axles. Fig. 3 is a vertical sectional view on line 3—3 of Fig. 2. Fig. 4 is a top plan view of a track cleaner and wheel, and Fig. 5 is a detail perspective view of one of the plugs.

50 Referring now to the drawings by characters of reference, the numeral 1 designates the track to be cleaned while the numeral 2 designates the car wheel. This car wheel is mounted on the usual axle 3 and is surrounded by the cleaner which is designated

generally by the numeral 4. This track cleaner comprises the two separate bodies 5 and 6 which are formed with the recesses 7, the end walls of which are curved to conform to the curvature of the wheel. These 60 recesses 7 are to receive the wheel and the two separate sections 5 and 6 are held together by the bolts 8 which also serve as supports for the plugs which will be more fully hereinafter described. 65

Formed near each end of the body are the semi-circular recesses 9 which align with each other and form openings for the reception of the plugs 10, which plugs comprise the cylindrical body 11 having formed therein suitable longitudinal slots 12 for the reception of the bolts 8. These plugs may be formed of Babbitt-metal or any other suitable wear resisting material and it will be apparent that due to the longitudinal slot 12, 70 the plugs may be vertically adjusted to their respective openings and held in such adjusted position by the bolts 8. 75

It will be apparent from the foregoing that in use the device is placed in position 80 on the track so that the wheel 2 is received within the recess 7 formed by sections 5 and 6 and when in this position the plugs 10 will engage the upper surface of the track and space the lower surface of the bodies 5 and 6 from the track. In this way it will be seen that wear on the bodies will be prevented and as the plugs are worn down at the lower ends, they may be adjusted by loosening the nuts of the bolts 8 and sliding 90 the plugs farther in. After the plugs have been worn at their lower ends to the limit they may be removed and reversed so that the upper ends will engage the track and it will thus be seen that a practically unlimited number of adjustments is obtainable. It will also be apparent that after the plugs become entirely worn out, a new set of plugs may be substituted and thereby wear on the body of the device is eliminated. 95 100

While in the foregoing there has been shown and described the preferred embodiment of this invention, it is to be understood that such changes may be made in the combination and arrangement of parts as will fall within the spirit and scope of the appended claims. 105

What is claimed is:—

1. A track cleaner of the character described including a body, and removable 110

plugs adjustable within said body to engage the track and hold the body clear of the track.

2. A track cleaner of the character described including a body, plugs within the body to hold the same clear of the track, and means to adjustably secure the plugs within the body.

3. A track cleaner of the character described comprising a pair of coöperating bodies, each of said bodies being formed with a recess, the recesses coöperating and forming an opening for the reception of the tie wheels, plugs within the bodies and means to adjustably hold the plugs in position in the bodies to hold the bodies spaced from the track.

4. A track cleaner of the character described including a pair of coöperating

bodies, said bodies being provided with recesses in their adjacent faces, said recesses conforming to the curvature of the car wheel on which the device is used, the bodies also having arcuate recesses near each end, plugs fitted within the arcuate recesses, bolts extending through the bodies near each end and through the arcuate recesses, the said plugs having slots for the reception of the bolts and nuts on the ends of the bolts to adjustably hold the plugs in their various positions in the body.

In testimony whereof I affix my signature in presence of two witnesses.

CHARLEY W. LYNCH.
